DESIGN FOR A BANDSTAND

Nathaniel W. Raphael, South Orange, N. J.

Application December 31, 1937, Serial No. 74,025

Term of patent 7 years

To all whom it may concern:

Be it known that I, Nathaniel W. Raphael, a citizen of the United States, and a resident of South Orange, in the county of Essex and State of New Jersey, have invented a new, original, and ornamental Design for a Band Stand, of which the following is a specification, reference being had to the accompanying drawing, forming part thereof.

Fig. 1 is a front view of the band stand embodying my new design.

Fig. 2 is a sectional view of the band stand.

I claim:

The ornamental design for a band stand as shown.

NATHANIEL W. RAPHAEL.
